UNITED STATES PATENT OFFICE.

JOHN D. FATE AND EGBERT M. FREESE, OF PLYMOUTH, OHIO.

COMBINED CLAY-CRUSHER AND TILE-MACHINE.

SPECIFICATION forming part of Letters Patent No. 293,000, dated February 5, 1884.

Application filed November 12, 1883. (No model.)

To all whom it may concern:

Be it known that we, JOHN D. FATE and EGBERT M. FREESE, citizens of the United States, and residents of Plymouth, in the county of Richland and State of Ohio, have invented 5 certain new and useful Improvements in Combined Clay-Crushers and Tile-Machines; and we do hereby declare that the following is a full, clear, and exact description of the invention, which will enable others skilled in the art to which it appertains to make and use the same, reference being had to the accompanying seven sheets of drawings, which form a part of this specification, and in which—

15 Figure 1 is a perspective front view of our combined clay-crusher and tile-machine. Fig. 2 is a perspective rear view of the same. Fig. 3 is an end view of the main frame from the rear. Fig. 4 is a plan or top view of said frame, showing the adjustable box or bearing for the main shaft, and also the fixed box for the same. Fig. 5 is an end view of the main frame from the front, showing the construction of the adjustable box in detail. Fig. 6 is a vertical cross-section through the crusher-rolls and feed-chamber, with their adjustable scrapers. Fig. 7 is a plan or top view of the feed-chamber, with its lateral wings or extensions. Fig. 8 is a vertical cross-section through 20 the same on line α α . Fig. 9 is a plan or top view of the main frame with its shafts and gearing. Fig. 10 is an end view of the feed-chamber, showing the feed-spiral with its central shaft. Fig. 11 is a longitudinal sectional view of the feed-chamber, showing the inside feed-spiral and the fixed studs or knives. Fig. 12 is a rear elevation of the machine, showing the arrangement of the intermeshing gear-wheels for operating its several parts; and 25 Fig. 13 is a side elevation of the machine.

Similar letters of reference indicate corresponding parts in all the figures.

Our invention has relation to machines for the manufacture of drain-tile and similar ware, 45 and has for its object to simplify the construction of machines of that class, as well as to facilitate the operation of manufacturing tile.

To this end our improvement consists, first, in the combination, with a feed-chamber, which 50 may be of any suitable shape and construction for feeding the clay through the dies or molds,

of two or more crusher-rollers for crushing the clay, which said rollers are operated by the same gearing and mechanism which operate the feed or forcing mechanism in the feed-chamber; and, secondly, in the improved construction and combination of parts of the tile-machine proper, all as hereinafter more fully described.

On the accompanying seven sheets of drawings, Figs. 1, 2, and 13, show the complete machine—that is, the combined clay-crusher and tile-machine, as we prefer to construct it—while the remaining figures refer to details of construction. In the said figures, F denotes the main frame or bed of the machine, which is mounted upon legs f of suitable height. This frame is provided at its rear end with a fixed box or shaft-bearing, A', and at its front end with an adjustable box or shaft-bearing, 60 A, the construction of which is illustrated more clearly in Fig. 5 of the drawings, from which it will be seen that the box is fitted loosely into a recess, a, in the front end of the frame, and fastened to the same by means of 65 threaded bolts b b. The threaded ends of these bolts are inserted through oblong slots or apertures c in the wings or lateral extensions d of the box, thus permitting of lateral motion of the box by loosening the bolts; and so 70 its lateral adjustment is effected by means of set-screws e, bearing with their inner ends against the beveled or slanting sides of that part of the box which projects down into the recess a. Thus it will be seen that by 75 loosening the bolts b b and adjusting the set-screws e the box A may be adjusted in frame F, so as to be in a line with the fixed box A' at the opposite end of the frame, whereby we are 80 enabled to regulate the exact position of the main shaft within the feed-chamber or clay-receiver K. This chamber (shown at K in the drawings) is provided with lateral wings or 85 extensions k, which rest upon and are bolted to the rearwardly-extending arms F' F' of frame F by bolts inserted through the bolt-holes f'. Chamber K has an opening, K', in the top, and its front end, which extends out over frame F, is provided with a flange or collar, K², for the attachment of the neck or extension H, which is fastened removably upon the collar K² by bolts or screws h, inserted 90

through the flanges. The molds or dies are fastened to the front end of the extension H by means of brackets H' and screws h', inserted through said brackets, as shown more clearly 5 in Fig. 13 of the drawings. Inserted through the bottom of the feed-chamber are studs or knives S, fastened to the under side of the chamber by nuts s. These studs or knives operate to cut and mix the clay as it is forced 10 against them by the revolution of the sectional spiral or feed-auger N. This feed-spiral is shown in detail in Figs. 10 and 11 of the drawings, from which it will be seen that it consists of a series of spiraled propeller-shaped blades 15 fastened upon and projecting from opposite sides of collars N', fitting upon the squared main shaft G², and kept at the proper distance apart from one another by collars or tubular washers O. These collars are of such a width 20 as to space the propeller-collars N' sufficiently far apart from one another to permit their flanged spirals or propeller-blades to pass on opposite sides of the fixed studs or knives S, without touching the same, by the revolution 25 of the shaft, as will appear more clearly by reference to Fig. 11 of the drawings.

In order to prevent the clay from adhering to the crusher-rollers R R, which are mounted above the feed-chamber, we provide the top 30 part of said chamber with adjustable scrapers I, provided with screw-threaded lugs i, through which adjusting-screws I' are inserted, the heads of which bear against wedge-shaped blocks I², fastened upon the lateral wings or 35 extensions k of the feed-chamber. By adjusting the screws I', it will be seen that the scrapers I may be moved so as to bring their beveled edges in contact with the rolls R, so as to take up wear as the scrapers are gradually 40 worn away by the revolution of the rolls.

Clay is fed to the feed-chamber through the aperture K' in its top part, which is below and in a line with the crusher-rolls R, where these face each other, as will appear more 45 clearly by reference to Fig. 6 of the drawings. The clay is fed to these rollers through a hopper, L, and the journal-boxes O' of the crusher-rollers are made adjustable in the end plates, O², in substantially the same manner as shown 50 in Fig. 5 for the lateral adjustment of box A, whereby the roller-shafts P may be properly adjusted relative to each other, so as to bring their respective rollers R the proper distance apart, and thus crush or comminute the clay 55 to the required degree of fineness.

By reference to Figs. 9 and 12 on Sheet 6, it will be seen that the main shaft G² has an extension, G', upon which is keyed two cog-wheels, g and G. The smaller of the two, g, 60 meshes with the gear-wheel Q upon the projecting end of one of the roller-shafts P, while the large gear-wheel G meshes with a pinion, T, keyed upon shaft U, which has its bearings upon boxes on the top of plate F, and the outer end of which is provided with a drive-pulley, V. Thus it will be seen that when pulley V is rotated by an endless belt from a steam-

engine, or any other suitable motive power, the crusher-rollers are caused to revolve toward each other, as indicated by the arrows 70 in Fig. 6, at the same time that the feed mechanism is operated.

From the foregoing description, taken in connection with the drawings, the working of our improved machine will readily be understood without requiring extended explanation. Clay being thrown into the hopper is seized by the rolls as these revolve toward each other, and drawn through between them, thus crushing small stones, lumps, and other substances 80 contained in the clay, and otherwise crushing, grinding, and preparing the same for being molded into tile, bricks, or other ware. But besides crushing and preparing the clay, it will be seen that the rolls also operate as feed- 85 rolls or force-rolls to feed and force the crushed clay through the aperture K' into the feed-chamber K, where it is met by the feed mechanism, which feeds the clay out through the extension K², neck H, and the dies or molds 90 which are fastened at the front end of the latter. The studs or knives S prevent the clay from revolving with the feed-spiral, and also serve, as hereinbefore stated, to cut the mass of clay, and thus assist in its thorough mixing 95 into a homogeneous mass before it reaches the dies or molds at the outer end of the chamber. There may be one, two, or more rows or series of these studs fastened to the bottom and inner sides of the feed-chamber, and we desire 100 it understood that we do not limit ourselves to only one row, as shown in the drawings.

While we prefer to use only two crusher-rollers and arrange them as shown in the drawings, thereby causing them to force-feed the 105 crushed clay into the feed-chamber in the manner hereinbefore described, it is obvious that there may be more than two of these rollers, and that they may be located at a higher distance above the feed-chamber, so as to drop the 110 crushed clay into the same without any force-feed, or into a chamber or receptacle placed between the crusher-rollers and the feed-chamber; but we prefer the arrangement shown in the drawings for the reason that by forcing 115 the crushed clay into the feed-chamber and into direct contact with the feed mechanism it facilitates the operation of the machine and produces a better article by compacting the clay more solidly than can be done by the feed 120 mechanism alone.

Having thus described our invention, we claim and desire to secure by Letters Patent of the United States—

1. The combination, in a tile-machine, of 125 the frame having the fixed shaft-bearing A' and a recess, a, near the feed-chamber, the adjustable box A, having slots c in its wings or extensions and inclined sides, bolts b, sliding in said slots, set-screws e, bearing with their 130 ends against the inclined sides of box A, and the feeder-shaft G' G², as and for the purpose shown and set forth.

2. The combination of the feed-chamber

having a longitudinal opening at its upper side and laterally-projecting extensions *k*, the crusher-rollers, the beveled blocks *I*² upon the extensions, the scrapers having female-threaded perforated lugs *i*, and the set-screws *I'*, as and for the purpose shown and set forth.

3. In a tile-machine having a cylindrical feed-chamber, the combination of a revolving shaft, collars secured upon the shaft and provided each with two spiral flanges having a twist of one-half revolution in opposite directions, and having the ends cut off perpendicular to the shaft, spacing-collars inserted between the flanged collars, and knives or studs

inserted in the bottom of the feed-chamber 15 and projecting up in and nearly filling the spaces between the perpendicular ends of the flanges, as and for the purpose shown and set forth.

In testimony that we claim the foregoing as 20 our own we have hereunto affixed our signatures in presence of two witnesses.

JOHN D. FATE.
EGBERT M. FREESE.
